UNITED STATES PATENT OFFICE

LAWRENCE CARR STEELE, OF BEAVER, PENNSYLVANIA.

WIRE-WIPING APPARATUS.

1,078,176.

Specification of Letters Patent. Patented Nov. 11, 1913.

Application filed February 2, 1912. Serial No. 674,981.

To all whom it may concern:

Be it known that I, LAWRENCE CARR STEELE, residing at Beaver, in the county of Beaver and State of Pennsylvania, a citizen 5 of the United States, have invented or discovered certain new and useful Improvements in Wire-Wiping Apparatus, of which improvements the following is a specification.

10 In the process of galvanizing steel wire, the relatively short lengths of drawn wire are usually spliced together to form a continuous length, which is drawn successively through an annealing oven, bath of acid, 15 water and molten zinc, and a wiper. Wiping such wire, after it has passed through the bath of molten zinc, is an essential step in the process of its manufacture. In the first place, the wiping accomplishes a large 20 saving in the quantity of zinc used per unit length of wire; and, in the second place, when the wire is not wiped, the zinc coating will scale off when the wire is twisted. The apparatus heretofore employed for such 25 wiping has usually consisted of a pair of oppositely disposed wipers (consisting of holders provided with removable pads) between which the wire passes, the said wipers being movable to and from wire-wiping 30 position. In the operation of such apparatus it has been found necessary, in order to prevent injury to the pads, to move the wiper from operative position at such times as the splices or joints pass by. Fur- 35 thermore, it has been found that the best wiping is accomplished when the pads are intermittently replaced or adjusted in their holders. Both of these steps have been accomplished simultaneously. The workman, 40 who may be attending the apparatus, observing a splice approaching, moves the wipers from operative position; and, while in such removed position, he adjusts or replaces the pad in the holder, and then causes 45 the wiper to return again to operative position. On account of the speed of the advancing wire it has been found that, during such times as the wiper is held in inoperative 50 position, a substantial length of the wire passes by unwiped, and such length must, of course, be removed and used as scrap.

My invention relates to wire-wiping apparatus, and the object of my invention is to

provide an apparatus, which will efficiently 55 wipe an advancing length of wire, and which will reduce to a minimum the amount of unwiped wire adjacent to the splices.

In the accompanying drawing, which forms part of my specification, Figure 1 is 60 an end elevation of a portion of a series of wipers embodying my invention; Fig. 2 is a sectional view, taken on the line II, II, Fig. 1, showing a wiper in normal operative position; and Fig. 3 is a view similar to 65 Fig. 2 and taken on the line II, II, Fig. 1, showing the preferred operation of the wiper as a splice passes by.

In the figures like parts are indicated by 70 like numerals.

In the practice of my invention, I arrange a series of wipers in such a manner that they may act successively upon an advancing length of wire; and in such a manner that, during the interval which elapses while 75 one wiper is moving away from and the other toward wiping position, a splice may pass by without injuring either wiper. To such an end I preferably mount upon rotatable disks 1 and 2 a series of pad holders 80 3, 4, 5, 6 and 3^a, 4^a, 5^a, 6^a, respectively; and I preferably provide the said disks with teeth 7, to the end that the disks may rotate together. As will be seen, the said several pad-holders, which may be of any desired 85 form, but as shown herein are cylindrical cup shaped receptacles, are so mounted upon the disks that the pad-holders will come to wire wiping position in pairs, the pairs in this particular arrangement forming, when 90 suitably provided with pads 14, wipers 3, 3^a, 4, 4^a etc. The disk 1 may be rotatably mounted upon a cylindrical shaft 8; and the disk 2 may be rotatably mounted upon a suitable slot-provided sleeve 9, which in 95 turn may be mounted upon a fixed angular shaft 19, and may be held yieldingly toward the disk 1, as by springs 11 mounted, as shown, in the slot 12.

In the operation of my wiping apparatus, as thus far described, a wire 13 (see Fig. 1), moving from left to right as indicated by the arrow a, may be wiped by the wiper 3, 3^a; and, when a splice (such as is illustrated at 15) is about to pass between 100 the said wiper 3, 3^a, the workman in charge of the apparatus may rotate the disks in any desired manner, and preferably in the 105

direction of the moving wire. After the splice has passed beyond the previously operative wiper, a further rotation of the disks will be effective to bring a second wiper 6, 6^a into operative position.

In addition to the apparatus above described, my invention further resides in effecting automatically the successive operation of the series of wipers. Such an end 10 may be attained in any desired manner and may be adapted to any form of wipers. In the particular wipers shown herein, such an end may be attained by providing means for holding the wiper-provided disks 1 and 15 2 from rotating, by reason of the frictional contact of the advancing wire 13 with the operating pads 14; and further by so arranging the said holding means that they will be rendered ineffective by the advance of a 20 splice in the wire.

The holding-means preferably consists of a trigger, provided on one end with a notch 16, adapted to engage successively teeth 17, secured to the disk 2, and provided on the 25 other end with a slot 18, through which the advancing length of wire passes. The trigger is pivoted, as at 29, to a support 23, and may be held yieldingly in tooth-engaging 30 position by a spring 20. In this construction it is desired to have the teeth 17 correspond in number to the number of wipers mounted on the disk; and the arrangement is such that each disk 17, when engaged by the notch 16, is effective to hold 35 one of the wipers 3, 3^a, 4, 4^a, etc., in operative position. Such holding-means may be rendered ineffective, when a splice advances toward the wipers, by so proportioning the slot 18 that the smooth wire will pass freely 40 therethrough, but that a splice 15 will engage the sides of the slot and move the trigger from its holding position.

It will be understood of this construction that, when the disks are not held from 45 rotation, the advancing wire will, by its frictional engagement with the wiper, cause the disks to rotate; and by such rotation one wiper (as shown herein at 3, 3^a) will pass from wiping position, and the next 50 wiper (6, 6^a) will advance to operative position, their further advance being checked by the notch 16 engaging the next successive stop 17. Furthermore, it will be seen that during such time as one wiper is moving 55 from operative position and the other advancing thereto, the splice will pass by without coming in contact with either wiper, as is shown in Fig. 3 of the drawing. In order to more certainly effect sufficient rotation of the said disks 1 and 2 to cause the succeeding wiper (as shown herein at 6, 6^a) to advance to operative position, I 60 preferably provide one of the disks, such as the disk 2, with a series of outwardly-extending fingers 19, preferably grooved at 65

the ends as shown and arranged in alternation with the pad-holders; and I provide abutment, such as rollers 21 and 21^a over which the advancing wire may pass. The said rollers are arranged to oppose the 70 fingers 19, and the fingers are so disposed with relation to the wipers that, as a wiper passes beyond frictional engagement with the wire, a finger will come into such frictional engagement and cause the disks to continue to rotate until stopped by the trigger. The operation of such arrangement is particularly illustrated in Fig. 3, where the wiper 3, 3^a is shown as passing from operative position, the wiper 6, 6^a advancing to operative position, and a finger 75 19 being engaged, and caused to move onward, by the advancing wire 13.

The apparatus heretofore described may be used singly, or a number of such series of 80 wipers may be mounted together to the end that a plurality of wires, moving in parallel relation to each other, may be simultaneously wiped. Such an arrangement is particularly illustrated in Fig. 1, wherein I 85 have shown a series of disks 1 mounted upon a common shaft 8, and a series of co-operating disks 2 mounted upon a common shaft 10. These shafts may be secured to a suitable frame 22, in any desired manner, 90 the said frame being but partly shown in the drawings.

It will be understood that my wire-wiping apparatus may be used to advantage for 95 other purposes than that herein described. Furthermore, it will be understood that any 100 desired number of wipers may be arranged to operate successively upon an advancing length of wire, the number shown herein being selected for convenience of illustration.

I do not wish to limit myself to the construction shown herein, or to the details of 105 such construction, for obviously many changes may be made by those skilled in the art without departing from the spirit of my invention.

I claim as my invention:

1. In a wire-wiping apparatus, the combination of a rotatably mounted member having a plurality of pad-holders and a corresponding number of abutments secured thereto, and a pivotally mounted finger having one arm held yieldingly in the path of said abutments to engage therewith and a second arm extending in the path of an advancing length of wire, said second finger arm being adapted to be engaged and moved by a splice in such wire.

2. In a wire-wiping apparatus, the combination of a pair of rotatably mounted disks, means for coördinate rotation of said disks, a series of pad-holders secured to each of said disks and arranged thereon to coöperate in pairs, and means for hold-

- ing said disks against rotation, said holding-means adapted to be rendered ineffective by a splice on an advancing length of wire, substantially as described.
- 5 3. In a wire-wiping apparatus the combination of a pair of disks each provided with a series of wiping pad-holders effective successively to wipe an advancing length of wire, the said disks rotatable by the advance of such wire to bring successive pad-holders to wiping position, a finger lying in the path of such wire and normally holding the said disk against rotation and in wire wiping position, the said finger adapted to be rendered ineffective by the advance of a splice in such wire to hold the said disk against rotation, substantially as described.
- 10 4. In a wire-wiping apparatus, the combination of a pair of rotatably mounted disks, means for coördinate rotation of said disks, and a series of pad-holders secured to each of the said disks and arranged thereon to coöperate in successive pairs to wipe an ad-
- 15 vancing length of wire, one of the said disks being yieldingly mounted to move transversely of the line of advance of such wire, and means for holding said disks against rotation while coöoperating pairs of

pad-holders are wiping a continuous length 30 of wire, substantially as described.

5. In a wire-wiping apparatus, the combination of a pair of rotatably mounted disks each provided with a series of pad-holders and with interlocking teeth, a series 35 of abutments secured to one of the said disks, and a finger adapted to engage successively the said abutments, and thereby hold said disks against rotation, substantially as described.

40 6. In a wire-wiping apparatus, the combination of a pair of rotatably mounted disks, a series of pad-holders secured to each of said disks and arranged thereon to coöperate in pairs, a series of outwardly extending 45 fingers secured to one of said disks and lying one between each of said pad-holders, a series of abutments secured to said finger-provided disk, and a trigger yieldingly held within engagement range of said abutment, substantially as described.

In testimony whereof I have hereunto set my hand.

LAWRENCE CARR STEELE.
